PAGE 2

*Fig. 4.*Figure 1 is a front perspective view of a portable comfort kit in position for use, showing our new design.

Figure 2 is a view similar to Fig. 1, but with certain portions of the comfort kit stowed for transit.

Figure 3 is a view of the kit in the completely closed, transit position.

Figure 4 is a view similar to Fig. 1, with the kit suspended from a bulkhead in functional position.

The articles depicted in broken lines are for illustrative purposes only. The undisclosed side of the comfort kit is substantially the same in appearance as the side shown.

We claim:

The ornamental design for a portable comfort kit, substantially as shown and described.
